UNITED STATES PATENT OFFICE

EDWARD P. TUFTS, OF BOW, NEW HAMPSHIRE

SAWMILL

Application filed September 2, 1932. Serial No. 631,520.

This invention relates to sawmills and particularly to the head block mechanism by which the knees of the carriage are advanced after each board or slab has been cut to position the log for a fresh cut and by which the knees are retracted to place them in a position to have an uncut log placed on the carriage. In many sawmills the forward advance of the knees of positioning the log after each cut is accomplished through a manually-operated pawl and ratchet mechanism, and the return movement of the knees to their retracted position is accomplished by means which is actuated by the movement of the carriage.

One of the objects of my present invention is to provide a novel construction by which the pawls of the pawl and ratchet mechanism will be automatically released when the mechanism for retracting the knees is rendered operative, thus obviating any possibility that the pawls might be in engagement during such return movement.

In order to give an understanding of the invention I have illustrated in the drawings a selected embodiment thereof which will now be described after which the novel features will be pointed out in the appended claims.

Fig. 1 is a perspective view with parts broken out illustrating a sawmill embodying my invention;

Fig. 2 is a fragmentary plan view of the pawl-releasing mechanism;

Fig. 3 is a view taken on the line A—A, Fig. 2.

In Figs. 2 and 3 the parts of the sawmill which are of usual construction are illustrated in dotted lines and the parts embodying the invention are shown in full lines.

The sawmill comprises the usual frame 1 which includes the rails 2 and 3 on which the carriage 4 rides back and forth. The frame 1 is provided with the extension 18 which supports the saw arbor 5 carrying the saw 6, said saw arbor being driven from a driving pulley 7. The carriage 4 has the usual knees 8 mounted thereon which are adapted to be moved transversely of the carriage. In the present construction these

knees are mounted on a knee-supporting slide, indicated at 9, which is arranged to have movement transversely of the carriage 4. Journalled in the supporting slide is a shaft 10 which extends longitudinally of the carriage and which is provided at its ends with pinions 11 which mesh with racks 12 stationarily secured to the carriage 4.

A suitable pawl and ratchet mechanism is employed for turning the shaft in a direction to feed the slide 9 with its knees 8 forward. Such pawl and ratchet mechanism comprises a ratchet wheel 13 fast on the shaft 10 and a feed pawl 14 which is pivotally connected at 50 to an operating lever 15 and is adapted to co-operate with the ratchet wheel 13.

The lever 15 is pivotally mounted on the shaft 10 and it is provided with an arm 16 at its upper end which terminates in a handle 17. The handle is situated within convenient reach of the operator who generally stands on one side of the sill 2 adjacent the frame extension 18 on which the saw arbor is mounted. By manipulating the lever 15 the operator can turn the shaft 10 and thus advance the slide 9 to the desired extent.

Fig. 19 indicates a stop pawl pivotally mounted at 41 and adapted to engage a ratchet or toothed wheel 51 which is fast on the shaft 10. The teeth of the ratchet 13 are somewhat coarser than the teeth of the ratchet 51 as usual in sawmill feed devices.

Means are provided for retracting the slide 9 by movement of the carriage. For this purpose the carriage has journalled therein a vertical shaft 20 carrying at its upper end a pinion 21 which meshes with a rack 22 mounted on the slide 9. The lower end of this shaft 20 is provided with a friction wheel 23 which is adapted to engage the side face 24 of a longitudinally-extending member 25. The member 25 is mounted for movement toward and from the rail 3. Said member is normally in position where the face 24 is out of engagement with the friction wheel 23 but when the operator wishes to retract the slide 9 he shifts the position of the member 25 away from the rail 3 to bring the friction face 24 thereof into engagement with the friction

wheel 23. With the parts in this position the movement of the carriage on the rails will rotate the friction wheel 23 and shaft 20 and thereby shift the position of the slide 9 through the pinion 21 and rack 22.

This longitudinally-extending member 25 is connected to the rail 3 through two links 26 and is held in its retracted position through the medium of a spring 27. The member 25 is moved into its operative position through the movement of a treadle 28 pivotally mounted in bearings 29 which are connected to the rail 2. This treadle has the downwardly-extending end portion 30 which is connected by a cord 31 to one end of the member 25. When the treadle is depressed a pulling force will be applied to the connection 31 which will move the longitudinally-extending member 25 away from the rail 3 and the links 26 serve to maintain the face 24 of said member always in parallel relation with the rails. Such movement of the member 25 brings the face 24 into engagement with the friction wheel 23 as above described with the result that the movement of the carriage on the rails will serve to shift the slide 9 on the carriage.

The present invention provides novel means whereby the shifting of the longitudinally-extending member 25 into its operative position will automatically release the pawls 14 and 19 so as to permit the free backward rotation of the shaft 10. This release of the pawls is secured by a pawl-releasing mechanism which is rendered operative by the member 25 when it moves into its operative position.

The carriage 4 has suspended therefrom an arm 32 which is pivotally mounted at 33 and which carries at its lower end a wheel 34 adapted to be engaged by the longitudinally-extending member 25 when the latter is moved into its operative position. This arm 32 is connected to a pawl-releasing member 35 which is mounted on the carriage and extends transversely thereof. Such pawl-releasing member is supported on arms 36 which are pivoted at one end in bearings 37 secured to the carriage and which are pivoted 50 at their upper ends to the member 35.

46 indicates a shaft which is journaled in bearings 48 mounted on the carriage 4. One end of said shaft is provided with an offset portion 49 which is pivotally connected to the 55 pawl-releasing member 35 and the other end is provided with an arm 47 which is pivotally connected to the upper end of a link 38, the lower end of which is pivotally connected to the arm 32.

60 When the longitudinally-extending member 25 is moved into operative position into engagement with the friction wheel 23 said member will engage the wheel 34 at the lower end of the arm 32 and swing the latter to the left Fig. 3. Such swinging movement of the

arm 32 operates through the link 38 to turn the shaft 46 and the turning movement of the shaft operates through the arm 49 to raise the dog-releasing member 35, such member swinging about the arms 36 during its rising movement. Such rising movement of the member 35 serves to release the pawls 14 and 19 by the following mechanism.

The ratchet wheel structure 13, 51 has associated therewith a curved bar or quadrant member 39 which is provided at one end with an inwardly-directed arm 40 that is pivotally mounted on the stud 41 carrying the pawl 19. This extension 40 has a finger 45 extending laterally therefrom which underlies the pawl 19.

The feed pawl 14 has a link 42 pivotally connected thereto, which link is provided with a pin or projection 43 that extends across the upper edge of the quadrant 39 so that when said quadrant is turned about its axis 41 the upward swinging movement thereof will operate through the link 42 to raise the pawl 14 out of engagement with the ratchet 13.

The lower end of the quadrant member 39 has a laterally-extending foot 44 secured thereto which normally rests on the pawl-releasing member 35. When said pawl-releasing member is raised as above described it acts through the foot 44 to swing the quadrant member 39 about its pivot 41 thereby by raising the feed pawl 14 out of engagement with the ratchet 13 as above described. Such swinging movement of the quadrant member also operates through the finger 45 to raise the stop pawl 19 so that both pawls 14 and 19 are disconnected from the ratchet structure by the swinging movement of the quadrant member 39.

By the use of the swinging arm 32, the link 38 and dog-releasing member 35, the pawls 14 and 19 will be automatically disconnected from the ratchet structure by the movement given to the longitudinally-extending member 25 by the depression of the treadle 28.

The clearance between the member 25 and the roll 34 is less than that between said member and the wheel 23 so that the pawls will be released before the member 25 is brought into operative engagement with the wheel 23.

There is herein shown means for releasing the pawls manually. The arm 16 is provided with a lateral projection 53 which is connected by a link 54 to the quadrant member 39 so that an upward swinging movement of the arm 16 will operate to raise the quadrant member 39 and thus disconnect the pawls.

I claim:

1. A sawmill having a carriage provided with transversely-extending racks, rails on which said carriage travels, a knee-support

ing slide mounted on the carriage to move transversely thereof, a shaft journalled in said slide, pinions on the shaft meshing with said racks, a ratchet on said shaft, a manually-operated feed pawl co-operating with the ratchet for rotating the shaft to advance the slide, a stop pawl to prevent retrograde movement of the slide, slide-retracting means actuated by the movement of the carriage, a member pivoted to the carriage and operating when swung upwardly to release both pawls from the ratchet, a vertically-movable pawl-releasing member mounted on the carriage and extending transversely thereof, means to raise said pawl-releasing member when the slide-retracting means is rendered operative, and means actuated by the vertical movement of said pawl-releasing member to swing said pivoted member upwardly thereby to release the pawls.

2. A sawmill having a carriage provided with transversely-extending racks, rails on which said carriage travels, a knee-supporting slide mounted on the carriage to move transversely thereof, a shaft journalled in said slide, pinions on the shaft meshing with said racks, a ratchet on said shaft, a manually-operated feed pawl co-operating with the ratchet for rotating the shaft to advance the slide, a stop pawl to prevent retrograde movement of the slide, slide-retracting means actuated by the movement of the carriage, a member pivoted to the carriage and operating when swung upwardly to release both pawls from the ratchet, a vertically-movable pawl-releasing member mounted on the carriage and extending transversely thereof, means to raise said pawl-releasing member when the slide-retracting means is rendered operative, and connections between said pawl-releasing member and said pivoted member which are operative in all positions of the slide and by which the rising movement of the pawl-releasing member swings the pivoted member upwardly and thereby releases the pawls.

3. A sawmill having a carriage provided with transversely-extending racks, rails on which said carriage travels, a knee-supporting slide mounted on the carriage to move transversely thereof, a shaft journalled in said slide, pinions on the shaft meshing with said racks, a ratchet on said shaft, a manually-operated feed pawl co-operating with the ratchet for rotating the shaft to advance the slide, a stop pawl to prevent retrograde movement of the slide, slide-retracting means actuated by the movement of the carriage, a member pivoted to the carriage and operating when swung upwardly to release both pawls from the ratchet, a vertically-movable pawl-releasing member mounted on the carriage and extending transversely thereof, means to raise said pawl-releasing member when the slide-retracting means is rendered

operative, said pivoted member having an extension adapted to be engaged by the pawl-releasing member when the latter moves upwardly thereby to give the pivoted member its swinging movement by which the pawls are released.

In testimony whereof, I have signed my name to this specification.

EDWARD P. TUFTS.
